UNITED STATES PATENT OFFICE.

WILLIAM J. KELLY, OF JAMAICA, NEW YORK, ASSIGNOR TO THOMAS MOONEY, OF DOUGLASTON, NEW YORK.

DOOR-CHECK AND OPEN-DOOR-LOCKING DEVICE.

1,171,053.

Specification of Letters Patent.

Patented Feb. 8, 1916.

Application filed August 14, 1914. Serial No. 856,729.

To all whom it may concern:

Be it known that I, WILLIAM J. KELLY, a citizen of the United States of America, residing in Jamaica, Long Island, county of 5 Queens, and State of New York, have invented certain new and useful Improvements in Door-Checks and Open-Door-Locking Devices, of which the following is a specification.

10 This invention relates to door check devices of any construction or mode of operation having a door-closing arm held to the door and coupled as by a pivoted link device to the door frame.

15 The invention has for its object to provide for such door checks a simple and efficient means or mechanism whereby an opened door may be locked open and to varying extent as may be desired by the 20 occupant of a room for which the door affords entrance or exit.

The invention consists in a door check having on its door-actuating arm a latch device adapted to automatically engage the 25 check casing and thereby lock the door open; and to engage the casing at different places for locking the door at different angles of opening; the parts being relatively arranged to automatically lock the door open only 30 after the door has been opened farther than is necessary to permit convenient entrance or exit.

The invention also includes details of construction of the door locking devices as combined with old standard parts of the door check, all as hereinafter described and claimed.

In the accompanying drawings, Figure 1 is a sectional plan view showing in full lines 40 the door check applied to a closed door and indicating by dotted lines the first position in which the door may be locked open. Fig. 2, a front elevation showing the closed door. Fig. 3, an enlarged detail plan view of a preferred construction with the door actuating arm broken away. Fig. 4, a vertical section taken on the irregular line *a—a* in Fig. 3. Fig. 5, a detail plan view showing the door locking latch head in horizontal section. 50 Fig. 6, a sectional plan view taken on the irregular line *b—b* in Fig. 4, and Fig. 7, a detail plan of a modification hereinafter described.

In the drawings the numeral 1 indicates a 55 door and 2 its frame. To the door is fixed

the check casing preferably comprising a main body or barrel portion 3, and a top or end cap 4, which is revolubly adjustable on the barrel. A shaft 5 has inner bearings in a transverse partition of the casing barrel 60 6 and is fixed within a sleeve 6 of the ratchet 7, said sleeve having an outer bearing in the casing cap 4. The door-closing arm 8, is fixed to the shaft 5, and carries a pawl 9, adapted to any one of the peripheral notches 65 of the ratchet 7, for holding under any required torsion a coiled spring 10, opposite ends of which are held to the ratchet sleeve 6 and casing barrel 3 respectively. The outer end of arm 8 is coupled to one end 70 of a lengthwise adjustable two-part link device 11, the other end of which is pivoted to the door frame 2.

In carrying out this invention in a preferred manner there is formed on or fixed 75 to a top edge portion of the casing cap 4, a cam block 12, preferably having two edge cam surfaces 13, 14, and also provided with a central edge notch 15 into which is adapted to enter the inner head portion 16 of a 80 sliding latch 17 which has any suitable bearings on the door closing arm 8, and is normally retracted as by a spring 18, until it strikes a stop pin 19 in the arm for always holding the latch out of contact with the 85 cam block notch 15. Said cam block may have additional edge notches 20, 21, shown 90 in Fig. 7 of the drawings, and for a purpose 95 hereinafter explained. In the preferred construction the casing barrel 3 has at its upper end a series of slots or perforations 22, 23, 24, each adapted to receive the inner end of a radially adjustable screw or pin detent 25 fitted in the edge flange of the casing cap 4.

In the operation of the invention as shown in Figs. 1 to 6, inclusive, and when the casing cap detent 25 is adjusted in the 100 casing barrel slot 22, the latch end 16, as the door is opened, will ride upon the cam surface 13, until the latch enters the cam block notch 15, which occurs when the door is opened for about sixty degrees of arc and 105 the door will be locked at this angle of opening represented by the dotted lines in Fig. 1 of the drawings. Should the casing cap 4 be adjusted on its barrel 3, to allow 110 the detent 25 to enter the cam block notch

24, the door would be locked fully open at an angle of about ninety degrees, and when the detent 25 is adjusted in the barrel notch 23, the door will be locked open at an intermediate angle between sixty and ninety degrees.

It may be specially noticed that by reason of the relative positions of the automatic latch 17, the notched cam block, the detent 25, and the door closing arm 8, the door is never locked open until it has been opened fully to the sixty degree angle position, and therefore the door may at any time be opened to a less extent and will not then be locked open and also will be automatically closed by the spring actuated arm 8, and link 11, in usual manner. As a door opening of less than sixty degrees is ample to permit entrance or exit of any one person it is obvious that the latch mechanism 12 to 17, will desirably remain inoperative during all ordinary use of the door. The locked-open door may at any time be forcibly closed, at first by hand pressure on the door sufficient to cause the latch to ride up the inclined wall of the casing notch 15, and be freed therefrom, and finally by usual action of the door check spring 10, arm 8, and link 11. Should the door be opened to any extreme position beyond the ninety degree angle, the latch head 16 will ride upon the other cam block face 14, as the door is next forcibly closed, first by direct action of the spring actuated arm 8 until the latch 17 enters the casing notch 15, and then by hand pressure sufficient to force the latch from said notch to finally permit the spring 10 to automatically complete the door closing operation. As shown in Fig. 7 of the drawings the cam block 12, having cam surfaces 13, 14, may have its edge notches 15,

20, 21, so located that the latch 17 on arm 8 will act in any one of these notches to lock the door open in the respective above named three angular positions, and without using 45 the casing cap detent 25, acting in casing barrel notches 22, 23, 24 as will readily be understood.

I claim:

1. The combination with a door check 50 casing of a spring-actuating arm mounted to turn about the axis of the casing, a notched cam having cam surfaces of less radius than the casing and having its inner ends located over the top of the casing and 55 within the periphery thereof, and a pawl carried by the arm engaging the cam and moved radially outward thereby and adapted to engage the notch of the cam.

2. In a door check the combination with a 60 spring barrel, a shaft extending into the barrel, a sleeve surrounding said shaft and carrying a ratchet wheel, a spring attached to the barrel and to the sleeve, a cap for the barrel having a notched cam thereon arranged in the same plane with the ratchet wheel and partially surrounding it, a 65 spring-actuating arm mounted to turn relatively to said sleeve, a pawl carried by the arm and engaging the ratchet wheel, and another pawl mounted on the arm and moving radially toward and from the ratchet wheel but held at all times out of engagement therewith, and which is adapted to 70 ride on said notched cam and engage the notch thereof.

In testimony whereof, I have hereunto subscribed my name.

WILLIAM J. KELLY.
